Primary Examiner — Leanne Was-Englehart(74) *Attorney, Agent, or Firm* — Birch, Stewart, Kolasch & Birch, LLP(57) **CLAIM**

We claim the ornamental design for a television with frame, as shown and described.

DESCRIPTION

FIG. 1 is a perspective view of a television with frame showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a partial enlarged view thereof;

FIG. 9 is another perspective view thereof shown with environment; and,

FIG. 10 is another perspective view thereof showing a state of the display screen thereof rolled to the frame.

The dot-dot-dash broken lines depict the limits of the enlarged views and form no part of the claimed design. The broken lines in FIG. 9 are for the purpose of illustrating an environment of use and form no part of the claimed design.
